DESIGN FOR A BOWL

Carl Schmitz, New York, N. Y., assignor to Verlys of America, Inc., New York, N. Y., a corporation of New York

Application November 26, 1941, Serial No. 104,343

Term of patent 7 years

To all whom it may concern:

Be it known that I, Carl Schmitz, a citizen of the United States of America and a resident of New York, in the county of New York and State of New York, have invented a new, original, and ornamental Design for a Bowl, of which the following is a specification, reference being had to the accompanying drawing, forming a part there-

I claim:

The ornamental design for a bowl, as shown and described.

CARL SCHMITZ.
